UNITED STATES PATENT OFFICE.

ADOLPH MORITZ, OF SCHWERIN, GERMANY.

MACHINE FOR WORKING RATTAN.

SPECIFICATION forming part of Letters Patent No. 224,212, dated February 3, 1880.

Application filed October 5, 1878. Patented in Germany, September 21, 1877.

To all whom it may concern:

Be it known that I, ADOLPH MORITZ, of Schwerin, in the Empire of Germany, have invented certain new and useful Improvements 5 in Machines for Dividing Twigs and Cane, of which the following is a description, reference being had to the accompanying drawings, forming part of this specification.

This invention, which is the subject-matter 10 of a patent of the German Empire dated September 21, 1877, issued June 12, 1878, and numbered 1,094, relates to machines for peeling, splitting, shaping, and dividing willow and other twigs and rattan or cane for various 15 purposes, including, by simply enlarging the proportions of the machine, the manufacture of hoops for casks or barrels.

The invention consists in a novel arrangement and construction of cutting or reducing 20 devices for subdividing the split portions of twig or cane into pieces of any desired widths.

Figure 1 is a front elevation of a machine constructed in accordance with my invention; Fig. 2, a plan of the same. Fig. 3 is a trans- 25 verse section, in part, on the line $x-x$; Fig. 4, a face view of a cutter-holder with attached cutters for radially splitting the twig or cane; Fig. 5, a transverse section, in part, on the line $y-y$; and Fig. 6, a front elevation of cer- 30 tain devices for peeling or barking the twigs before splitting or dividing them.

Referring in the first instance, or more particularly, to Figs. 1, 2, 3, 4, and 5 of the drawings, A A are the side frames of the machine, 35 connected with each other by means of a cross-table, B, over which the material to be operated on is introduced to the machine, either from the same side or from opposite sides of the machine, for the several operations to be 40 performed upon said material, accordingly as the machine may be constructed in this respect to suit the convenience of the manufacturer, or as other circumstances may direct.

C is a main driving-shaft, which may be rotated by any suitable power. Upon this shaft 45 is a spur-wheel, D, which serves, by means of gears E F, to rotate in their requisite directions upper and lower feed-roller shafts, G and H. The upper one, H, of these shafts is made 50 adjustable and yielding relatively to the lower one by means of screws b and springs c .

I and J are circumferentially-grooved feed-rollers on the shafts G and H. These rollers serve to feed the twigs or canes by or through the grooves d in them to radial splitting-tools 55 e, arranged to split the willow or cane into three, four, or other parts, as desired, but which are here represented as constructed or arranged to split the material into three and four parts, respectively, two sets of said cutters, of which there may be any number, being shown in the drawings as carried by a single holder, K, supported by the table B on the delivery side of said rollers. A grooved guide, L, arranged on the opposite or feed side of said 60 rollers, serves to direct the twig or cane to the grooved feed-rollers I and J. The upper roller, J, is raised or lowered according to the diameter of the twig or cane to be split, and the cutter-holder K is correspondingly adjusted 65 to centrally guide the willow or cane relatively to the splitting-tools e, and through circular apertures f in the holder K and a back plate, g. The cutter-holder K may thus be adjusted up or down by means of vertically-adjustable 70 supports h , attached to clips k , pivoted to stanchions l , and constructed to hook onto the upper roller-shaft, H, to retain the cutter-holder and its cutters in position against the 75 resistance of the cut, and to provide for the up or down adjustment of the cutters, together 80 with the upper feed-roller shaft.

From the lower end of the cutter-holder lugs h project downward through slots in the table, fitting sufficiently loosely in said slots to permit the cutter-holder to follow the movement of the clips to which it is pivoted. The cutter-holder, being pivoted nearer to the pivot of the clips than is the adjustable roller, will, of course, move a shorter distance than said roller, 90 so that the knives will preserve their proper location with respect to both upper and lower rollers.

Fast also on the shafts G and H are other rollers, M N, for feeding the longitudinally-split 95 portions of the twig or cane, after delivery from the cutters e, to a shaping or planing and reducing knife, O, said split portions or lengths being introduced to the rollers M N through any desired number of guides $m m$, adjustable 100 toward or from each other by slides $n n$, and the lower one, N, of these rollers being grooved

to receive the rounded portion of the twigs or cane. Said knife O, which acts upon the angular surfaces of the split portions of the twigs or cane, reduces said portions to the desired thickness.

To utilize these reduced split lengths or portions, it is desirable in many cases to subdivide them into strips of equal breadths. To this end said reduced split lengths or portions are introduced through an adjustable guide, P, between supplementary rollers Q and R on the shafts G and H. The lower one, Q, of these rollers has a plain peripherical surface; but the upper one, R, consists of a number of disks, w, having knife-like edges or peripheries. These disks are removable, and arranged at suitable distances apart by means of intervening washers. A loose-ring, r, is also arranged upon said roller, and the screw r', passing through the flange s, bears upon said ring and compresses the disks and washers between it and a flange upon the opposite end of the roller, so that it will be seen that the number of the cutters and their distance apart may be varied. By passing the originally divided and reduced strips through these disk-cutters said strips are cut into lesser strips of a breadth corresponding to the distances of the cutting-disks apart.

When operating upon twigs, which it is necessary to peel or bark before splitting, shaping, or reducing and subdividing them, I attach to one of the side frames, A, of the machine, in place of the guide L and cutter-holder K, for operation in connection with the feed-rollers I J, or without removing the guide L and cutter-holder K, for operation in connection with annularly-grooved special feeding-

rollers, peeling or barking devices or scrapers T U, Fig. 6. These devices T U have reverse arched or right-angle-shaped scraping-edges r s. One of these scrapers, T, is stationary and attached to the table B, in place, it may be, of the guide L, and the other, U, of said scrapers is carried by a bracket, a', and is movable up or down by means of a lever, b', through a treadle or otherwise, and a spring, c'. The twig to be barked is first introduced sufficiently between the scrapers T U to allow the rollers I J, or other rollers corresponding thereto, to get a fair hold upon it, and so that said rollers will draw the twig between the scrapers T U, the movable one, U, of said scrapers being in the meantime pressed down by hand or foot, and so that the sharp edges r s will strip the bark from the twig passing between the scrapers. In some cases, instead of the scraper U, a roller covered with rubber may be used for operation in connection with the scraper T.

I do not claim the devices for radially splitting the twigs or cane, for planing, shaving, or otherwise reducing the flat surfaces, or for scraping or peeling the twigs or cane, but merely describe them as useful adjuncts of my invention.

I claim—

The combination of the adjustable guide P, the plain roller Q, and the cutting-roller R, fitted with a series of adjustable cutting-disks, w, for subdividing into breadths the split rattan or twig, substantially as specified.

ADOLPH MORITZ.
